UNITED STATES PATENT OFFICE

2,188,113

CROSSOVER FOR OVERHEAD TROLLEY SYSTEMS

Richard Roy Holden, deceased, late of Highland Park, Ill., by Bertha Belle Holden, executrix, Highland Park, Ill., assignor, by mesne assignments, to R. Roy Holden, Inc., Chicago, Ill., a corporation of Illinois

Original application July 5, 1934, Serial No. 733,708. Divided and this application April 13, 1938, Serial No. 201,770

4 Claims. (Cl. 191—37)

This invention relates to a crossover and has special reference to a crossover suitable for use where the intersecting wire form a small angle.

More particularly the crossover of the present invention is designed to positively guide a current collecting member, whether mounted on a fixed or swivel harp, under the crossover so that the current collector will continue along the same wire, thereby preventing any possibility of the current collecting member switching from one wire to another, which may occur if no positive guide means are provided.

The crossover of this invention acts automatically and positively to direct the current carrying member, and may be used either in a single or double conductor trolley system. It has a minimum of moving parts, and may be comparatively light in weight and inexpensive to manufacture. Therefore, there is little possibility of the crossover becoming inoperative for any reason.

The present application is a division of application Serial No. 733,708, filed by Richard Roy Holden, July 5, 1934, and entitled "Overhead trolley system".

Other objects and advantages of the present invention will be apparent from the following description when taken together with the accompanying drawing in which latter:

30 Figure 1 is a bottom plan view of a crossover embodying the present invention.

Fig. 2 is a side elevation of the crossover shown in Fig. 1.

35 Fig. 3 is a central cross-sectional view of the crossover shown in Fig. 1.

Fig. 4 is a top plan view of the crossover shown in Fig. 1.

Fig. 5 is a cross-sectional view showing the pin and slot construction.

40 Referring to the drawing, there is shown a new form of simplified crossover embodying this invention. The crossover of the present invention may comprise a base member 66 having runners 67, 68, 69 and 70 depending therefrom. Perforated ears 71 are provided in the base member 66 adjacent the outer ends of the runners and perforated ears 72 may be provided adjacent the central portion of the crossing. These ears provide means for connection to the cross spans to 45 support the crossover in proper position. In forming the base member 66, a central aperture or opening may be provided in which the operating structure hereinafter to be described is positioned. As shown particularly in Fig. 1, adjacent 50 runners 67 and 68 and adjacent runners 69 and 55

70 may be formed in pairs with the oppositely disposed runners being substantially a continuation of each other.

The present crossover is particularly suitable where the angle between the intersecting trolley wires is extremely small. The inner ends of the runners may be tapered as shown in Fig. 1. In this way, sufficient distance is provided between adjacent runners to permit the flanges of current-collecting members to pass therebetween. 10 Means are provided for guiding a current-collecting member passing along runner 67 to the oppositely disposed runner 70 or along the runner 68 to runner 69, and vice versa. This may comprise a base plate 73 for attachment to the upper 15 side of the base member 66 over the central aperture provided therein, so that it may be easily removed from the base member 66. On the underside of the base plate 73 adjacent the ends thereof are substantially pointed runner members 74, 75, 20 76, and 77, which in effect are continuations of and, when in position, form the inner ends of the runners 67, 68, 69, and 70. A movable guide member 78 is pivotally mounted substantially 25 midway between the ends thereof to the base 25 plate 73. A stud shaft 79 extends upwardly through a bearing portion 80 on the top of the base plate 73 and is movably mounted therein so as to be capable of vertical movement as well as rotation. The ends of the movable member 78 30 are preferably pointed so that the sides thereof may engage and lie close to the respective pointed runners 74, 75, 76, and 77. Extending upwardly from the movable member 78 through apertures in the base plate provided therefor are portions 35 81. The portions 81 are preferably positioned not far distant from the ends of the movable member 78. Projecting from the portions 81 are pins 30 or similar members 82 which fit in slots 83 provided therefor in guide members 84. These slots 40 83, as shown particularly in Fig. 5, are preferably substantially V-shaped. They not only serve to guide the pins 82 and thereby the movable member 78 to operative position, but also support the movable member 78. When in normal operative position the pins 82 seat in the bottom or apex of the slots 83, and the lower surface of the movable member 78 projects below the pointed runner portions 74, 75, 76, and 77. This is shown in Figs. 3 and 5. The distance from the outer 45 sides of the runner portions 74, 75, 76, and 77 at the outer ends thereof to the opposite side of the pointed ends of the movable member 78 is made slightly less than the distance between the inner faces of the flanges of the current-collecting 50 55

members to be used therewith. With this construction, when a current-collecting member is moving along one of the runners such as the runner 67 on the base member, the inner face of the outer side of the current-collector engages the outer side of the runner member 74, and the other inner face of the opposite side of the current-collecting member engages the far side of the pointed end of the movable member 78. As it moves along the movable member 78, due to the widening thereof, the current-collecting member forces the member 78 toward the runner member 74 and, at the same time, due to the upward pressure on the current-collecting member, which pressure is ordinarily about 28 pounds, the movable member is moved upwardly and the pins 82 slide upwardly in the slots 83, so that the movable member 78 is urged into the position shown in Figs. 1 and 4. The movable member 78 is held in this position until the current-collecting member passes beyond the same and onto the oppositely disposed member 70, whereupon, due to the weight of the movable member, the same drops back into normal position with the ends of the movable member substantially midway between the runner portions 74 and 75 and the runner portions 76 and 77. With this construction a current-collecting member passing along any one of the members 67, 68, 69, and 70 will be automatically and positively guided to the oppositely disposed runner. Guide flanges 84a are preferably provided on the base member 66. The movable parts are reduced to a minimum so that the whole crossover may be inexpensive to manufacture and will continue in use for a long period of time without the necessity for any repairs.

Further modifications will be apparent to those skilled in the art, and it is desired, therefore, that the invention be limited only by the prior art and the scope of the appended claims.

Having thus described the invention, what is claimed and desired to be secured by Letters Patent is:

1. A trolley crossover having runners thereon at an angle to each other and a unitary movable member normally positioned in a lower inactive position, said member being mounted so as to be capable of movement in directions upwardly and sidewardly so as to be moved into operative position adjacent to and in substantial alignment with either of said runners by contact of a current-collector therewith for guiding a current-collector from or to said runners, said crossover being provided with a slot having two portions extending at an angle to each other, means on said movable member for co-operating with said slot to guide said movable member to position adjacent either of said runners upon contact of a current-collector therewith, said movable member being so shaped and positioned that a current-collector passing along either runner will be guided onto said movable member when the latter is in said inactive position.

2. A trolley crossover having runners thereon at an angle to each other and a unitary movable member normally positioned in a lower inactive position, said member being mounted so as to be capable of movement in directions upwardly and sidewardly so as to be moved into operative position adjacent to and in substantial alignment with either of said runners by contact of a current-collector therewith for guiding a current-collector from or to said runners, said crossover being provided with a slot extending upwardly and to each side of the lower portion thereof, means on said movable member for co-operating with said slot to guide said movable member to position adjacent either of said runners upon contact of a current-collector therewith, said movable member being so shaped and positioned that a current-collector passing along either runner will be guided onto said movable member when the latter is in said inactive position.

3. A trolley crossover having runners thereon at an angle to each other and a unitary movable member normally positioned in a lower inactive position, said member being mounted so as to be capable of movement in directions upwardly and sidewardly so as to be moved into operative position adjacent to and in substantial alignment with either of said runners by contact of a current-collector therewith for guiding a current-collector from or to said runners, said crossover being provided with a substantially V-shaped slot, means on said movable member for co-operating with said slot to guide said movable member to position adjacent either of said runners upon contact of a current-collector therewith, said movable member being so shaped and positioned that a current-collector passing along either runner will be guided onto said movable member when the latter is in said inactive position.

4. A trolley crossover having runners thereon at an angle to each other and a unitary movable member normally positioned in a lower inactive position, said member being mounted so as to be capable of movement in directions upwardly and sidewardly so as to be moved into operative position adjacent to and in substantial alignment with either of said runners by contact of a current-collector therewith for guiding a current-collector from or to said runners, said crossover being provided with a pair of spaced V-shaped slots, means on said movable member adjacent the ends thereof for cooperating with said slots to guide said movable member to position adjacent either of said runners upon contact of a current-collector therewith, said movable member being so shaped and positioned that a current-collector passing along either runner will be guided onto said movable member when the latter is in said inactive position.

BERTHA BELLE HOLDEN,
Executrix of the Estate of Richard Roy Holden,
Deceased.
